UNITED STATES PATENT OFFICE.

THOMAS DOW AINSLIE, OF METUCHEN, NEW JERSEY, ASSIGNOR TO THE ROESSLER & HASSSLACHER CHEMICAL COMPANY, OF NEW YORK, N. Y., A CORPORATION OF NEW YORK.

TREATING TEXTILE MATERIALS.

Application filed August 29, 1924. Serial No. 734,852.

To all whom it may concern:

Be it known that I, THOMAS Dow AINSLIE, a citizen of the United States, and resident of Metuchen, in the county of Middlesex 5 and State of New Jersey, have invented certain new and useful Improvements in Treating Textile Materials, of which the following is a specification.

In subjecting textiles to the action of 10 solutions as in dyeing or bleaching operations uniform results are dependent upon a uniform treatment. If, as in the bleaching of cotton goods with peroxide liquors, the fibres are not evenly penetrated with the 15 treating solution and the entire mass of goods being bleached is not kept at a fairly uniform temperature even results may not be obtained. The material in some parts of the mass may be bleached to a greater 20 degree than the remainder. In extreme cases parts of the material may be scarcely bleached at all.

Further, since the effective strength of a dyeing or bleaching bath usually decreases 25 with time and use it is necessary to have all parts of the load thoroughly penetrated at a uniform temperature by the active liquor as soon as possible after treatment has begun.

As these considerations are especially important in connection with the treating of 30 textiles with peroxide bleach baths, I shall describe my invention in terms of its use with these solutions though not limiting its 35 employment to bleaching liquors.

One of the main difficulties in attempting 40 to bleach a mass of cotton material in a kier without using an excessive quantity of bleach liquor is the danger of not uniformly treating the fibres throughout all parts of the kier. The source of the trouble is usually channeling or the fact that the treating liquor does not percolate evenly 45 through the entire mass of goods. Another reason for poor penetration is that the fabric, yarn or raw stock may be tightly packed so that the center of the mass offers 50 too great a resistance to the liquor; also the pressure exerted by any gas which may be released within the material may tend to 55 make the goods more buoyant, which hinders complete penetration considerably. Uneven treatment may be readily discovered 60 since the parts of the material which were

penetrated last or least will not be as well 55 bleached as the balance of the goods. One reason for this is that in bleaching with peroxide the strength of the treating liquor is constantly lessening; therefore, complete penetration of the mass must be made 60 within a reasonable time or unevenness is bound to occur. For this reason the kier or vat is very often not loaded to its full capacity so that the liquor will have more opportunity to come in contact with the 65 fibres in all parts of the kier. Under any conditions it is essential that the mass be completely penetrated before the decomposition of the hydrogen peroxide has occurred to any great extent, or those parts 70 which are penetrated after the bleaching liquor has lost a large part of its strength or available oxygen will not be bleached as thoroughly as the portions of the load which have had the benefit of the full bleaching 75 power of the bath.

The object in processing material in a kier, especially in bleaching with hydrogen peroxide, is thus to treat the maximum amount of material with a given quantity 80 of liquor in a minimum of time since this means a low cost for chemicals per pound of goods, and a lower equipment investment. In arranging any apparatus or equipment to accomplish the desired result, provision 85 must always be made for uniformly treating the material. In some cases in order to obtain thoroughly satisfactory results the kier must be loaded without packing the goods tightly with the result that the capacity of the kier is reduced. Often the chemicals are divided into two batches and the goods treated twice being removed between treatments and given a light wash 90 before being placed back into the kier. Either method reduces the capacity of the kier considerably. In some cases satisfactory results are obtained with the single boil, although under the existing methods the time required to completely penetrate 100 the mass of material is considerable.

After considerable investigation of commercial plants and prior art, and experimentation, I have devised a novel method and apparatus which eliminates the foregoing difficulties. According to my invention, a combination of multiple vertical and horizontal, preferably radial inflows of 105

liquor through a packed mass of yarn, piece goods, raw stock, or the like, with discharge of the merged streams, with the ratio of vertical flow to horizontal or radial flow 5 predetermined so that the latter is preferably equal to or in excess of the former according to conditions, solves the problem, and enables very unexpected and desirable economies to be realized in bleaching and 10 washing masses of piece goods, yarn, raw stock, etc. By radial flow, I mean flow from within the mass toward the walls of the vat tending to distend the mass toward the walls, as distinguished from inward flow 15 from the walls, tending to compress the mass away from the walls. An advantage of the invention is that expensive new construction is not required to change over existing plants, which when so changed over, 20 may have an output of double their previous capacity, with greater economy in heat, labor, water, power, peroxide and other chemicals per unit of goods treated, and will give more uniform and pleasing 25 results. The same economies will be realized in new plants embodying my invention, with but little if any more initial investment.

In my invention, by the combination of 30 vertical and horizontal or radial inflows, liquor of the same strength is at any time acting throughout the mass, which avoids one cause of uneven bleaching action. By reason of the relatively stronger horizontal 35 streams intercepting the vertical streams, there is a quick penetration with continuous breaking up or disturbing action in the interior of the mass, tending to reduce the expansion of the mass due to trapped gas, and 40 channeling, with the result that the entire mass of material is thoroughly saturated with the treating liquor at all times. A radial or horizontal flow alone, or a vertical flow alone, would not accomplish the novel 45 effects of the two in combination.

I have obtained the most satisfactory results by having about 70% of the liquor flow horizontally or radially, and the balance flow downwardly, but do not restrict 50 myself to these proportions in my broad claims.

Fig. 1 represents the circulating system as attached to a kier which is designated as 1. 55 22 is a screen or perforated bottom to support the goods. 2 is a drain pipe from the well 21 of the kier. Valve 18 permits draining the kier thru pipe 3 to the waste line. 4 is the pipe which leads from the drain of the kier thru valve 5 to the pump 6. 7 is a 60 discharge of the pump to the tubular heater 8 from whence the liquor flows thru pipes 9 and 10. 11 and 12 are valves. 20 is a perforated spray pipe for discharging the liquor over the goods. 13 is a pipe which feeds pipes 14 and 16 to discharge the

liquor radially from spray-head 17. Valve 19 prevents the liquor from going down pipe 15 to the pump 6. By the regulation of the various valves as explained hereafter under the Routes Nos. 1, 2, and 3, the direction of the liquor may be controlled.

Fig. 2 shows the invention including multiple spray-heads 17, applied to a large vat 25. The liquor is drawn from the well of the vat 21 thru the drain pipe 2 thru the valve 5 thence thru the pipe 26 to the pump 6 and thence to pipe 24 and spray-heads 17. The liquor may also be taken thru the spray-heads 17 thru the pipes 16 and 14 thence 30 thru the pipe 15 thru the valve 19 thence thru the pipe 26 to the pump 6. From the pump the liquor is discharged thru pipe 7 thru the heater 8 thence thru either pipe 11 to the distributing pipe 24 or the liquor may be sent thru pipes 12, 14 and 16 to be discharged thru 17. The liquor may also be controlled as shown under the headings Route Nos. 1, 2, and 3.

Spray-head 17 is a pipe which may well extend two-thirds the height of the kier or vat. The upper portion is perforated and may be covered with a cloth to better diffuse the liquor if desired. If preferred the pipe may be constructed of heavy screen or wire mesh of small size so as to get a better lateral distribution of the liquor upon its discharge. 24 is a distributing pipe in the open vat which runs in one continuous line around the top of the vat. We have found that this gives a good distribution of the bleach liquor in case of leakage or excessive loss by evaporation since the top of the goods will be kept saturated.

In the preferred form of the invention, a vat or kier will be provided with a vertical perforated pipe for discharging liquor laterally or radially within the mass, and a top pipe for discharging liquor on top of the mass, with combined discharge at the bottom to the circulating pump intake, thence 105 through a heater if used, and back through the pipes, means being provided for proportioning the respective flows as above stated. In large equipments, there will be a plurality of vertical pipes as in Fig. 2, so as 110 to secure the desired rapid penetration before the liquor weakens.

The design of the special pipe which extends within the material will depend upon the type of fabric being processed as well as the size and shape of the vat. It may extend into the load of goods to about two-thirds of their height. The pipe may be designed of a pear shape if preferred so as to avoid the shoulders catching the material when the machine is being unloaded. By spacing these pipes so that the amount of goods around each pipe is the same very satisfactory results are obtained due to the fact that the liquor is brought into intimate 125 130

contact with the center of the mass of material which is ordinarily difficult to penetrate. In the case of a kier a single center pipe may be used if desired.

5 I have also found that one great advantage of this circulating system is that washing may be carried out to a remarkable degree by circulating the liquor as indicated in Route 1 which assists materially in reducing the time required for washing after 10 coming from the kier or vat. The effectiveness of the washing is due to the radial or horizontal stream together with the vertical flow penetrating throughout the mass 15 of material.

By drawing the liquor from the well of the kier and discharging approximately 70% of the output of the pump into the center of the mass of cloth and the remaining 30% 20 on top as described later under the paragraph heading "Route No. 1" there are many advantages to be gained both in the thorough penetration of the fibres; the uniformity of treatment; releasing with more ease 25 the gas liberated in bleaching; less air is trapped and carried into the mass of material with the solution, and a lower labor cost.

The liquor may be moved in the following routes:—

30 *Route No. 1.*—The liquor is taken from the well of the kier thru the pump and heater and then 70% of the liquor is discharged thru the center pipe and the remaining 30% over the surface of the goods. This is done by referring to Fig. 1. The liquor is carried from the kier out thru the pipe 2 thence thru the pipe 4 to the pump 6, valves 18 and 19 being closed and 5 35 opened. The liquor is now passed from the pump 6 thru the pipe 7 to the tubular heater 8 thence thru the discharge pipe 9, valve 12 being opened so that approximately twice the quantity of liquor will pass thru 40 it as passes thru valve 11. The liquor going thru the valve 12 is passed thru pipes 13, 14 and 16 to be discharged within the center of the mass thru the spray-head 17. The remaining third of the liquor which 45 passes thru valve 11 is discharged over the surface of the goods thru the spray pipe 20.

50 *Route No. 2.*—The liquor will be drawn thru the spray-head 17 thence thru the pipes 16, 14 and 15 to the pump 6, valves 5 and 55 12 being closed and 19 and 11 opened. From the pump 6 the liquor would pass thru pipe 7 thence thru the heater 8 thru pipes 9 and 10 to be sprayed over the surface of the goods through pipe 20.

60 *Route No. 3.*—The liquor will be drawn out of the well and spray-head 17 thru pipes 2, 4, 16, 14 and 15 into the pump 6, valves 19 and 5 being opened and 18 closed. From the pump 6 the liquor would go thru pipe 7 65 thru the tubular heater 8 thru the pipe 9 and

sprayed out of the pipe 20, valve 12 being closed and valve 11 opened.

The preferred mode of operation is to operate according to Route No. 1. It will be found when working with liquors which liberate gases that if at the end of each hour or so the valves are arranged so as to circulate through so as to circulate a minimum of liquor through the vertically discharging spray head 20 for 20 or 30 minutes then a portion of the gas which ordinarily gives more or less trouble will be removed. In the present method of working when bleaching with peroxides by circulating the bath the liquor being thrown constantly on top of the goods tends to seal the oxygen beneath it whereas with my system by taking the liquor from the bottom or the well of the kier or vat and forcing it into the center of the mass assistance is actually given the gas to escape. This oxygen, unless liberated, creates considerable pressure within the mass of cloth and also makes the load buoyant which in turn, of course, exerts a great deal of pressure at the top of the kier. The method sometimes employed for assisting this gas to escape is to stop the circulation and allow the gas to work itself out through the liquor. My improved system, however, as stated above is of great benefit in releasing this gas.

The arrangement and connections of kier, pump, pipes, valves, and spray-heads herein shown has several advantages over present apparatus in simplicity, compactness, 100 and flexibility, and a wide variety of textile treating processes can be carried out therewith.

In addition to the routes above mentioned, the apparatus disclosed will permit other 105 routes to be used as the operator may prefer, or for special purposes, whereas, so far as I am aware, apparatus heretofore devised has not been capable of such universal or wide variation.

110 What I claim is:

1. Method of treating goods packed in a kier or vat which consists in flowing multiple streams of treating liquor through the mass in a direction from within the mass outward toward the walls of the vat while simultaneously flowing streams of liquor transversely thereto through the mass, and withdrawing the merged streams at a distance from their places of entry.

115 2. The method of treating goods packed in a kier or vat which consists in forcing under positive pressure treating liquor in a plurality of streams from within the kier toward the wall of the kier so as to distend the material within the kier toward the wall of the kier, and simultaneously flowing streams of the treating liquor vertically through the kier.

120 3. The method of treating the goods

packed in a kier or vat which consists in flowing multiple streams of treating liquor through the mass in horizontal and vertical directions, the horizontal streams being greater than the vertical streams in the approximate proportions of 70 to 30, and withdrawing the merged streams at a distance from their places of entry.

4. The method of treating goods packed in a kier or vat which consists in flowing multiple streams of treating liquor through the mass in diverging and in downward directions, the diverging streams being under positive pressure and greater than the vertical streams, and withdrawing the merged streams at the bottom.

5. The method of bleaching goods packed in a kier or vat with bleaching liquor which consists in flowing multiple downward and diverging streams of bleaching liquor through the mass thereby assisting any gas present in escaping to traverse an elongated lateral and upward path against the downward liquor flow, the diverging streams being under positive pressure, and withdrawing the merged streams at the bottom.

6. The method of treating goods packed in a kier or vat which consists in flowing multiple streams of treating liquor through the mass in radial and downward directions, the horizontal streams being greater than the vertical streams in the approximate proportions of 70 to 30.

7. The combination with a kier or the like having a bottom outlet for liquor, a plurality of multiple inlets spaced from the outlet to discharge multiple streams of liquor in diverging directions, and means for supplying liquor to said inlets in desired proportions.

8. The combination with a kier or the like having an outlet for liquor, of a vertical inlet having multiple diverging discharge apertures, a second inlet having multiple vertically discharging apertures, said inlets being spaced from the outlet, and means for supplying a major portion of liquor to the vertical inlet and a minor portion to the second inlet.

50 9. The combination with a kier or the like having an outlet for liquor, of means for flowing multiple streams vertically through goods packed therein, means for flowing multiple streams horizontally through the goods, a pump connected to said outlet to withdraw the merged streams and supply said streams, and means for connecting said pump to withdraw liquor

through said horizontal stream means to supply said vertical stream means. 60

10. The combination with a kier or the like having an outlet for liquor, of a spray-head for discharging liquor to flow vertically through goods packed therein, a vertical spray-head within the kier for discharging liquor laterally through the packed goods, a pump connected to the outlet to supply said two heads, a pipe connecting said vertical spray-head to the pump intake and valve means for controlling said vertical spray-head to discharge liquor into or withdraw liquor from the kier. 65

11. In combination with a kier or the like having an outlet for liquor, a plurality of inlet pipes in the kier having multiple diverging discharge apertures therein, a separate inlet pipe having multiple vertically discharging apertures, said inlets being spaced from the outlet, and a pump connected to said outlet to withdraw the merged streams and supply liquor to all said inlet pipes. 75

12. In combination with a kier or the like having an outlet for liquor, of means for conveying a supply of treating liquor to the interior of a mass of material packed in said kier and discharging it outward toward the walls of the vat, and means for directing a supply of treating liquor substantially vertically through said mass. 80 90

13. In combination with a kier or the like having an outlet for liquor, of means for introducing treating liquor at the top of the kier, and means for introducing treating liquor under positive pressure to points within a mass of goods packed in the kier. 95

14. The combination with a kier or the like having side retaining walls and a perforated supporting bottom, of an outlet for liquor below said perforated bottom, a spray head at the top of the kier for discharging liquor to flow vertically by gravity through the goods packed therein, a vertical spray head within the kier for discharging liquor radially under positive pressure through the packed goods, and a pump connected to the outlet and supplying said two heads. 100 105

Signed at Perth Amboy, in the county of Middlesex and State of New Jersey, this 28th day of August, A. D. 1924.

THOMAS DOW AINSLIE.

In presence of—
J. A. BRIMLOW.
